LAZY SUSAN OR SIMILAR ARTICLE

Clayton H. Laughlin, Minneapolis, Minn., assignor to Arthur Salm Inc., Chicago, Ill., a corporation of Illinois

Filed May 6, 1959, Ser. No. 55,791

Term of patent 14 years

(Cl. D44—10)

Fig. 2 is a top plan view;
 Fig. 3 is a bottom plan view;
 Fig. 4 is a front elevational view;
 Fig. 5 is a side elevational view;
 Fig. 6 is a sectional view taken on the line 6—6 of Fig. 2; and

Fig. 7 is a sectional view taken on the line 7—7 of Fig. 2.

The dominant features of my design are shown in full lines.

I claim:

The ornamental design for a lazy susan or similar article, substantially as shown and described.
